MULTICOLOR PRINTING PRESS

Paul F. Cox, Chicago, Ill.

Application January 16, 1934, Serial No. 706,876

25 Claims. (Cl. 101—186)

This invention is a novel traveling cylinder sheet printing press, especially designed and adapted for printing sheets in multi-colors.

The machine shown in the accompanying

5 drawings has a plurality of impression cylinders moving in an orbital path, a plurality of beds arranged to coact with the cylinders in the orbital movement of the latter, means for feeding sheets to and delivering them from each impression cylinder during each orbital movement of the latter, and a plurality of inking mechanisms one for each printing surface whereby ink is supplied to each printing surface for and during each orbital movement of the cylinders.

10 15 In the accompanying drawings I have illustrated one practical embodiment of the invention in a press whereby sheets may be printed in three colors on one side during each orbital movement of the cylinders, such press being provided with 20 duplicate impression cylinders arranged diametrically opposite each other and duplicate sets of form inking rollers arranged diametrically opposite each other, whereby two sheets may be printed in multi-color during each complete rotation of the crossheads carrying the 25 cylinders.

I will describe the machine shown in said drawings to enable others skilled in the art to adapt and use the same; but the invention in its 30 broader aspects is not limited to the specific construction and arrangement of parts shown in said drawings.

In said drawings:

Fig. 1 is a side elevation partly broken of a 35 complete printing press.

Fig. 2 is a vertical detail sectional view thereof.

Fig. 3 is a plan view of the press with some parts broken away.

Fig. 4 is a detail sectional view showing a 40 cylinder in position to take a sheet from the feeding devices.

Fig. 5 is a similar view showing a cylinder in position to deliver the sheet to the delivering devices.

45 Fig. 6 is a detail transverse sectional view of the printing beds.

Fig. 7 is a detail of the gripper tripping devices shown in Fig. 5.

The operative parts of the press are mounted 50 in suitable framing. The press shown has a feed board 1 from which the sheets can be fed by hand or mechanically to a transfer reel by which they are delivered to the impression cylinders 35 as they pass the said reel. The press 55 shown has two impression cylinders 35 journaled

at diametrically opposite ends of rotatable crossheads 33 and 34 mounted upon a main supporting shaft 32 by which the cylinders are moved in an orbital path.

During each half revolution of the crossheads 60 a cylinder will be moved from the sheet feeding devices 3 to the sheet delivering devices 61, (and vice versa), and in such movement the sheet will be successively presented by the cylinder to the printing surfaces on the three type beds 19, 19a, 65 and 19b disposed below the shaft 32 and adjacent the orbital path of the cylinders. In the machine shown these type beds are flat and the printing surfaces thereon will be flat; but the beds and printing surfaces may be curved if desired. The 70 impression cylinders operate alternately, and during each rotation of the crossheads two sheets may be printed in multi-color.

Mounted on the crossheads 33—34 in advance of each impression cylinder 35 are sets of form 75 inking rollers 52, 52a and 52b which are respectively adapted to ink the forms on beds 19, 19a and 19b. The sets of form inking rollers respectively receive ink from fountains 56, 56a and 56b during each rotation of the crossheads. Each 80 fountain may supply a different color, and the press is adapted to print three colors upon the sheet on each impression cylinder as it moves from the feed to the delivery. Means are provided whereby each set of inking rollers only 85 contacts with the form on the related bed; and mechanism is provided for properly distributing the ink on the form rollers before they ink the forms.

The press shown embodies various minor novel 90 details of construction as follows:

The feed devices

Sheets are fed on feed board 1 (Figs. 1 and 2) against a stop 2 and are picked up by the grippers of the feed reel, which as shown comprises four disks 3 mounted on a shaft 6, which shaft is moved step by step by a Geneva stop mechanism 4—5 stopping at a point where the sheet will be picked up by printing cylinder. The 100 Geneva member 4 is affixed to shaft 6, and has four radial grooves; and its driving member 5 is fixed on a shaft 7 (arranged inside of the side frame 31) and has two opposite arms provided with studs 8 adapted to engage the slots in member 4 to turn the latter; on shaft 7 is a double Geneva segment 4a adapted to lock member 4 during the intervals between engagements of studs 8 therewith. A sprocket 9 is fixed to shaft 7 and driven by a chain 9a from a gear 9b on 110

a stud 9c meshing with a pinion 9d on shaft 32. Shaft 7 is geared to rotate one to one with the crosshead 34 and disks 3 will rotate one fourth a revolution and feed a sheet to a cylinder at each one-half revolution of the crossheads.

The disks 3 have four sets of grippers, spaced 90° apart, for picking up sheets from feed board. Each set of grippers includes a shaft 10 extending through the disks and having a gripper 11 at each disk. The grippers are kept closed by a torsion spring 12 on each shaft. On one end of shaft 10 is an operating lever 13 for opening the grippers. To pick up a sheet from the feed board the operating lever 13 is caused to open the grippers by contacting with a stud 14 fixed to an adjacent part of the frame. As the feed reel starts to rotate lever 13 is released allowing the grippers to pick up a sheet, and when the reel comes to rest the sheet is in position to be taken by the grippers on an impression cylinder 35.

When an impression cylinder comes to the point of contact with the feed reel, the grippers on disks 3 are opened by a roller 15 (Figs. 1 and 4) on the end of crosshead, which comes into contact with and moves a lever 16 fixed to shaft 17, causing lever 18 (which is also fixed to shaft 17) to operate gripper shaft 10 opening grippers and releasing sheet to the impression cylinder.

The type bed and inking frame

The type bed is approximately semi-circular (see Figs. 1 and 6) and has three surfaces 19, 19a, 19b to carry the type forms or printing surfaces: And mounted above the type bed is an approximately semi-circular inking frame 20 fitted onto the type bed.

On the type bed are two bearer bars 21 (Fig. 2) for the impression cylinders. These bearers are type high and continue completely around the interior of the bed and inking frame. On the left hand side (Fig. 2) is a rack 22 meshing with the cylinder gears to cause cylinders to rotate. This rack consists of three straight sections 22 and segments 23-24 connecting them, and the end sections 22 connect with the ends of a semi-cylindrical segment 25 fixed in the inking frame.

The inking frame has an interior surface which acts as an ink plate to aid in grinding up ink. The inking frame also carries the feed shaft 6 and delivery shaft 77 and the ink fountains 56, 56a, 56b.

As shown each set of ink rollers 36 consist of three rollers, two composition form rollers toward the outside and a vibrator roller inside and in contact with the form rollers. The rollers are carried in adjustable bearings 50 which are carried in the carriages 51 mounted in sliding bearings in the crosshead by studs which allow the carriage to tilt. At each end of each form roller is a gudgeon 53 which allows the roller to contact only in its proper places. The vibrator roller 54 is carried in carriages 51 and is movable longitudinally to help cut up ink on form rollers. The movement longitudinally is controlled by a screw thread cut into the journal of roller. This screw thread is a right hand and a left hand thread and by means of a guide 55 fixed to carriage, causes the roller to move back and forth as it rotates.

Each ink fountain 56 (Fig. 1) is operated by a ratchet 57 and a lever 58 which is connected to bar 91 actuated by the cam 37 on crosshead. Said bar has a roller 59 to contact the cam, and

is held in position by a stud 60 in left hand frame 31.

Along the outside of both bed and frame are the bearer bars 26 for the gudgeons 53 of the ink rollers, these bars 26 are in general connected and constructed similarly to the cylinder bearers and the gear rack; but bars 26 are divided transversely into three sections (one section for each set of ink rollers); beside each printing surface only one section of the bars 26 is of same height as the type surface, thereby allowing only one set of inking rollers to supply ink to that particular surface, the other two adjacent sections of the bars being above type height cause other sets of ink rollers to pass without inking such surface. At the points of feed and delivery the bars are formed to raise all three sets of rollers to prevent ink smutting the paper on feed or delivery disks.

Adjacent each ink fountain one section of bars 26 is depressed to allow each set of rollers to contact only with its related ink supply. After passing the fountains the bars 26 are formed to permit each set of rollers to contact a related part, 27, 27a, 27b, of the ink plate.

The main shaft 32 carrying the crossheads 33-34 is driven by a gear 32a on outside of frame 31. Gear 32a may be driven from a gear 87 on drive shaft 86 by a train of intermediate gears 88 (Fig. 1) and shaft 86 may be driven by any suitable means. On the hub of the left hand crosshead is fixed the cam 37 controlling the ink fountain feeds.

Each impression cylinder 35 has a clamp 38 for the tympan and a reel rod 39 for drawing the tympan tight.

The sheet to be printed will be picked up by the cylinder grippers 40 at the point of contact with the feed disks 3 and carried over and presented to the three printing surfaces, and then released at point of contact with delivery disks 61. The grippers 40 are fixed on a shaft 41 which is operated by a lever 42. Thru the right hand journal of the impression cylinder extends the shaft 43 with cam lever 44 on outside and operating lever 45 on inside. The cam lever 44 is operated at the point of feed by a cam 46 and at the point of delivery by cam 47 both fixed to inside of frame 30.

The impression cylinders are carried in journals 48 movable in a radial direction and pressed outwardly by an adjustable spring 49. Affixed to the left hand side of each cylinder 35 is a gear 92 which engages an orbital rack formed of sections 22, 23, 24, 25 fastened to the type bed and inking frame.

The delivery and stacker

The delivery reel and mechanism for driving the disks 61 are constructed like the feed reel and its actuating mechanism having Geneva members 4x, 4ax, actuating lever 5x and pins 8x mounted on a shaft 7x driven by sprocket 9x and chain 9ax from a sprocket on stud 9b, with the following exceptions:—When the disks 61 rotate to a stop the grippers 62 are opened by the lever 63 coming in contact with a lever 64 fixed to the ink frame, see Figs. 5 and 6. When the impression cylinder arrives at point of contact with the delivery disks 61 it moves lever 64 and releases the disk grippers. The disk grippers are opened at the proper time to release the sheet, which drops into the stacker.

The stacker 66 is supported on each side by a roller chain with a counter weight 67 and guided by bars 68. The chains are carried over sprockets 150

69 fixed to shaft 70. On right hand end of shaft is a worm gear 71 in contact with a worm 72 on shaft 73, at the other end of which is a ratchet 74 and lever 75 which is operated by a connection 5 76 fastened in an eccentric position on end of shaft 77. The rotation of shaft 77 causes the stacker board to lower, in order to take care of the pile of delivered sheets.

10 *The impression throwoff*

To prevent the impression cylinders from contacting the printing surfaces when not carrying a sheet, the operator can depress a pedal 78 which rocks a shaft 79 upon which are fixed bell crank 15 levers 80 and similar levers 83 are pivoted on studs on the frame. Attached to these levers are rails 81 which, when the levers are properly rocked, are moved up parallel with and above the printing surfaces into position to be engaged by the 20 cylinder bearers 82 and prevent the cylinders contacting with the printing surfaces.

Operation

The sheets on feed board 1 are fed up to stop 25 2 and successively taken by the feed disks 3 and delivered to a cylinder 35 as it passes said disks. The sheets are presented by the cylinder successively to the type forms on the beds (19, 19a and 19b), each form being inked in advance of 30 the cylinder by its related set of inking mechanism (52, 52a and 52b). The printed sheet is then delivered to the delivery disks, and piled upon the stacker 66. The cylinders can be thrown off impression at any time desired by depressing the lever 78.

Preferably I employ duplicate impression cylinders and sets of inking mechanism in the machine, but in some cases only one cylinder and set of inking mechanism might be provided 40 but a plurality of impression cylinders and inking mechanisms are preferred in order to enhance the capacity of the press.

I claim:

1. A printing press having a type bed, and a 45 plurality of orbitally moving impression cylinders cooperating with the type bed.

2. In a printing press, a type bed, a plurality of orbitally moving impression cylinders cooperating with the type bed, means for feeding sheets to the cylinders in advance of the type bed, and means for delivering the sheets from the cylinders after passing the type bed.

3. In a printing press, a type bed, a plurality of orbitally moving impression cylinders cooperating with the type bed, means for feeding sheets to the cylinders in advance of the type bed and means for delivering the sheets from the cylinders after passing the type bed, and means moving with the cylinders for inking the printing surface 55 on the bed.

4. In a printing press, a type bed carrying a plurality of successive flat printing surfaces, and a plurality of orbitally moving impression cylinders successively cooperating with the flat printing surfaces during their orbital movement.

5. In a printing press, a type bed carrying a 70 plurality of successive printing surfaces, and diametrically opposed orbitally moving impression cylinders successively cooperating with the printing surfaces during their orbital movement.

6. In mechanism as set forth in claim 5, means whereby the impression may be thrown off.

7. In a printing press, a type bed carrying a 75 plurality of successive printing surfaces, a plurality of orbitally moving impression cylinders

successively cooperating with the printing surfaces during their orbital movement, inking devices, and means whereby each inking device supplies ink to only the related printing surface.

8. In a printing press, a type bed carrying a 80 plurality of successive printing surfaces, a plurality of orbitally moving impression cylinders successively cooperating with the printing surfaces during their orbital movement, means moving with the cylinders for individually inking the printing surfaces on the bed, means for feeding sheets to the cylinders in advance of the type bed and means for delivering the sheets from the cylinders after they pass the type bed.

9. In a printing press having a type bed, rotatable crossheads, and a plurality of impression cylinders mounted in the crossheads adapted to cooperate with the type bed as they are orbitally rotated by the crossheads.

10. In a printing press having a type bed, rotatable crossheads, a plurality of impression cylinders mounted in the crossheads and adapted to cooperate with the type bed as they are orbitally rotated by the crossheads, means for feeding sheets to the cylinders in advance of the type bed, 100 and means for delivering sheets from the cylinders after they have passed the type bed.

11. In a printing press having a type bed, rotatable crossheads, an impression cylinder mounted in the crossheads and adapted to cooperate with the type bed as it is orbitally rotated by the crossheads, inking rollers mounted on the crosshead in advance of the cylinder, an ink supply adjacent and exterior to the path of the cylinder, and means for distributing the ink to the form rollers 110 between the ink and the first type bed.

12. In a printing press having a type bed, rotatable crossheads, an impression cylinder mounted in the crossheads and adapted to cooperate with the type bed as it is orbitally rotated by the crossheads, means for feeding sheets to the cylinder in advance of the type beds, means for delivering sheets from the cylinder following the type beds after it has passed the type beds, inking rollers mounted on the crosshead in advance of the cylinder, an ink supply adjacent and exterior to the path of the cylinder, and means for distributing the ink to the form rollers between the ink supply 120 and the first type bed.

13. In a printing press having an approximately semi-circular type bed, rotatable crossheads mounted adjacent the type bed, opposite cylinders carried by the crossheads adapted to alternately contact with forms on the bed as the crossheads rotate, means for feeding sheets to the 130 cylinders at one end of the bed, and means for delivering sheets from the cylinders at the other end of the bed.

14. In combination with mechanism as set forth in claim 13, an ink supply adjacent the path of 135 the cylinder, an ink distributing member above the bed and between the ink supply and the feed, and form inking rollers carried by the crossheads adapted to distribute ink on the said distributing member.

15. In a printing press having an approximately semi-circular type bed, rotatable crossheads mounted above the type bed, a plurality of cylinders carried by the crossheads adapted to successively contact with forms on the bed as the crossheads rotate, means for feeding sheets to the cylinders at one end of the bed, and means for delivering sheets from the cylinders at the opposite end of the bed, inking devices, and means 145 150

whereby each inking device supplies ink to only means whereby the beds may be thrown off impression.

16. In a printing press having an approximately semi-circular type bed, rotatable crossheads mounted above the type bed, a plurality of cylinders carried by the crossheads adapted to successively contact with forms on the bed as the crossheads rotate, means for feeding sheets to the cylinders at one end of the bed, and means for delivering sheets from the cylinders at the opposite end of the bed, a plurality of inking supplies adjacent the paths of the cylinders, an ink distributing member above the bed and between the ink supplies and the feed, and form inking rollers carried by the crossheads adapted to distribute ink on the said member before applying ink to the forms.

17. In a printing press having a type bed, an orbitally moving impression cylinder cooperating with the type bed, levers adjacent the type bed, and bars carried by said levers adapted in one position to throw off impression.

18. In a printing press having a type bed, rotatable crossheads, an impression cylinder mounted in the crossheads adapted to cooperate with the type bed as it is orbitally rotated by the crossheads; oscillating levers adjacent the type bed, and bars carried by said levers adapted in one position to throw off impression.

19. In a printing press, an orbitally moving impression cylinder, an internally facing type bed and an internally facing ink distributor plate mounted adjacent the orbit of the cylinder, said cylinder being adapted to cooperate with the bed, and an inking roller moving with the cylinder adapted to alternately contact with the bed and with the inking plate.

20. In a printing press, rotatable crossheads, a plurality of cylinders mounted in the crossheads, a plurality of stationary type beds adjacent the orbit of the cylinders and adapted to be successively contacted by the cylinders during the orbital movement thereof, form inking rollers moving with the cylinders, and stationary ink distributing means in the orbital path of the cylinders opposite and intermediate the beds.

21. In mechanism as set forth in claim 20,

means whereby the beds may be thrown off impression.

22. In a printing press, rotatable crossheads, a plurality of cylinders mounted in the crossheads, a plurality of stationary type beds adjacent the orbit of the cylinders and adapted to be successively contacted by the cylinders during the orbital movement thereof, a plurality of ink distributing means exterior to and adjacent the cylinder orbit, and form inking rollers carried by the crossheads adapted to receive and distribute ink on said means and then apply ink to the beds.

23. In mechanism as set forth in claim 22, means whereby the rollers are caused to distribute ink only on the related portion of the distributing means, and to supply ink only to the related type bed.

24. In a printing press, rotatable crossheads, diametrically opposite impression cylinders mounted in the crossheads, a plurality of stationary type beds adjacent the orbit of the cylinders and adapted to be successively contacted by the cylinders during the orbital movement thereof, form inking rollers moving with the cylinders, and a plurality of ink distributing plates in the orbital path of the cylinders opposite the beds and inking rollers carried by the crossheads adapted to respectively distribute ink on the related plate and apply ink to the related bed.

25. In a printing press, rotatable crossheads, diametrically opposite impression cylinders mounted in the crossheads, a plurality of stationary type beds adjacent the orbit of the cylinders and adapted to be successively contacted by the cylinders during the orbital movement thereof, form inking rollers moving with the cylinders, a plurality of ink distributing plates in the orbital path of the cylinders opposite the beds and inking rollers carried by the crossheads adapted to respectively distribute ink on the related plate and apply ink to the related bed, means for feeding sheets to the cylinders in advance of the beds, and means for taking the sheets from the cylinders after passing the beds; and means for throwing off impression.
